United States Patent Office

Des. 208,564
Patented Sept. 12, 1967

208,564

CLOCK

Walter B. Herbst, Evanston, Ralph M. La Zar, Skokie, and Charles A. McLeod, Oak Park, Ill., assignors to Sunbeam Corporation, Chicago, Ill., a corporation of Illinois

Filed Dec. 12, 1966, Ser. No. 4,997

Term of patent 14 years

(Cl. D42—7)

FIG. 1 is a front elevational view of a clock embodying our new design;

FIG. 2 is a top plan view thereof; and

FIG. 3 is a sectional view taken substantially along line 3—3 of FIG. 1.

We claim:

The ornamental design for a clock, as shown.
